DESIGN FOR A SIGN FOR AUTOMOBILES OR THE LIKE

Wiley L. Moore, Atlanta, Ga.

Application September 10, 1938, Serial No. 79,833

Term of patent 14 years

To all whom it may concern:

Be it known that I, Wiley L. Moore, a citizen of the United States, residing at Atlanta, in the county of Fulton and State of Georgia, have invented a new, original, and ornamental Design for a Sign for Automobiles or the like, of which the following is a specification, reference being had to the accompanying drawing, forming part thereof.

I claim:

The ornamental design for a sign for automobiles or the like, as shown.

WILEY L. MOORE.
